ABSTRACT OF THE DISCLOSURE

A plurality of blocks are provided, each having inwardly extending flanges along the vertical side edges thereof. Each flange has in its outer face a recess extending vertically thereof, the recesses of facing flanges of adjacent blocks receiving a locking-rail. A clamping bolt extends throughout the facing flanges and the associated locking-rail to secure adjacent blocks to one another. The locking-rail extends a substantial distance inwardly of the innermost edges of the associated flanges. Insulating elements are fitted within the space between the flanges of each block, these insulating elements also extending a substantial distance inwardly of the innermost edges of the flanges of the associated block.

The present invention relates to a wall construction for buildings which comprises slab shaped rectangular blocks forming an outer shell, the blocks being assembled together by means of flanges facing inwards towards the body of the building and extending along the vertical side edges of the blocks, the flanges forming supporting elements, the outerface of each flange having a longitudinal recess or cavity extending a distance inwards from the outer edge, the recess receiving a locking-rail fitted between two blocks and against two facing flanges, the locking-rail forming an anchor for means securing the rectangular blocks, the recess being such that a joint exists between the inner edge of the flange and the recess.

This type of wall construction is previously known. It presents, however, the disadvantage that the components contained therein are difficult to assemble at the building site and therefore skilled tradesmen are required.

This disadvantage can be avoided, according to the invention, if the locking-rail projects a distance beyond the flanges and other, inner insulation, forming blocks or slabs, is directly fitted in the space between adjacent locking-rails.

According to one embodiment of the present invention, the locking-rail is penetrated by a bolt clamping the flanges together, and according to another embodiment of the invention, the joint between the outer faces of the flanges is sealed with sealing agent.

According to one embodiment of the invention, a second joint is provided between the locking-rail at the face of the locking-rail facing outwards from the body of the building and the limiting surface of the recess of two facing flanges. The second joint can also be filled entirely or partially with sealing medium.

According to one embodiment of the invention, an insulating air channel is provided between the inner surface of the outer shell and the other inner insulation forming the block or slab.

According to one embodiment of the invention, the inner surface of the outer shell is coated with a moisture preventing layer.

One embodiment of the invention will be more closely described whilst referring to the appended drawing, where

2

FIG. 1 shows the wall design in a perspective view, whilst FIG. 2 shows the same wall design in section.

The numeral 1 in the drawing indicates a slab shaped block which is provided with flanges 2. The block can be produced of concrete, asbestos cement, artificial stone or other material which can form a strong and suitable outer protection against damage and weather for the more susceptible insulating components of the body of the building. Between the flanges 2 of the block 1, the flanges forming supporting elements, insulating blocks or slabs 3 are fitted, according to any number of intermediary spaces between flanges. The thickness of the block 3 varies in relation to the material used and the desired heat value and sound insulation of the wall.

The blocks or slabs 3 could be comprised of glass wool, mineral wool, plastic, paper etc. with a surface layer of chips, paper, wallpaper sheets or the like. An air channel 4 is situated between the surface of the slab shaped block 1 facing the body of the building and the insulating block 3, in so doing the heat insulation is further improved. The inner surface of the slab shaped block can be coated with a layer serving as a moisture preventive e.g., asphalt.

The outer faces of the flanges 2 are provided with recesses or cavities which extend along the longitude of the flanges. These receive half the length of a locking-rail 6 which is suitably produced from wood. The depth of the recess 5 is so arranged that a channel 7 is formed between the raised parts of the flanges 2, the channel being sealed with the help of a sealing agent. A joint 8 is also arranged between the face of the locking-rail facing outwards from the body of the building and the bearing surfaces of the recess, the joint 8 being filled with a sealing agent. Both the slab shaped blocks are secured over the flanges with the help of a clamping bolt, one of the nuts being indicated by the numeral 9. As is apparent from the figure, the locking-rail 6 extends a distance beyond the edges of the flanges 2 in the direction of the body of the building. In so doing, a closed space is formed in which the insulating block or slab 3 is placed. A sheet 10 can be arranged on the inner surface wall construction. This sheet is fastened in a suitable way, e.g., nailed to the locking-rail surface that faces the body of the building.

In the above wall design a very reliable and durable wall construction is obtained and provides the exceptional advantage of allowing simple dismantling of the elements included without these elements being subjected to damage. The construction provides exceptional sound insulation and effective protection against flank-transmission.

The wall construction according to the invention can be utilized both as an inner wall and an outer wall construction.

55. What I claim is:

1. A wall construction for buildings comprising a plurality of slab shaped rectangular blocks forming an outer shell, said blocks each defining an outwardly facing surface and an inwardly facing surface, said blocks each having inwardly extending flanges formed along the vertical side edges thereof, each flange having in its outer face a recess extending vertically of the flange and from the innermost edge of the flange to a recess defining surface spaced from and substantially parallel with the outwardly facing surface of the associated block, the recesses of facing flanges of adjacent blocks receiving a locking-rail, means associated with said facing flanges and the associated locking-rail for securing adjacent blocks to one another to hold the blocks in assembled relationship, a channel being defined between spaced outer portions of the outer faces of the facing flanges of adjacent blocks, said locking-rail extending a substantial distance inward-

ly of the innermost edges of the associated flanges, insulating elements fitted within the space between the flanges of each of said blocks, said insulating elements also extending a substantial distance inwardly of the innermost edges of the flanges of the associated block to provide good heat and sound insulation and effective protection against flank-transmission, a space being defined between the outwardly facing surface of said locking-rail and said recess defining surfaces which define the outermost portion of the recesses of the associated facing flanges, said space being substantially filled with a sealing agent therewithin and in engagement with said outwardly facing surface of the locking-rail and said recess defining surfaces to bridge said channel and provide a seal at the inner end of said channel.

2. Apparatus as defined in claim 1 wherein said securing means comprises a clamping bolt, said locking-rail and the associated facing flanges having aligned holes formed therethrough for receiving said clamping bolt.

3. Apparatus as defined in claim 1 wherein said channel has a sealing agent disposed therewithin to seal the channel.

4. Apparatus as defined in claim 1 wherein an insulating air channel is defined between the outwardly facing portion of said insulating element and the inwardly facing surface of the associated block.

5. Apparatus as defined in claim 1 wherein said inwardly facing surface of each block is coated with a layer of moisture preventing material.

6. Apparatus as defined in claim 1 wherein each of said insulating elements is disposed directly inwardly of the flanges of the associated block.

7. Apparatus as defined in claim 6 wherein opposite side portions of each of said insulating elements is disposed closely adjacent the sides of the associated locking-rails.
